INVENTOR

UNITED STATES PATENT OFFICE.

MAX BRAUN, OF NEWARK, NEW JERSEY.

HARMONICA.

SPECIFICATION forming part of Letters Patent No. 392,405, dated November 6, 1882.

Application filed January 31, 1882. Serial No. 262,551. (No model.)

To all whom it may concern:

Be it known that I, MAX BRAUN, a citizen of the United States, residing at Newark, in the county of Essex and State of New Jersey, 5 have invented certain new and useful Improvements in Keyed Mouth-Harmonicas; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to that class of musical instruments in which the power for giving sound to the reeds is obtained from the mouth, whereby the power is more perfectly controlled and musical effects are obtained which cannot be secured by means of a bellows or other more 20 mechanical sources of power.

The invention consists in the arrangements and combinations of parts, substantially as will be hereinafter set forth, and finally embodied in the clauses of the claim.

Referring to the accompanying drawings, in which like letters of reference indicate corresponding parts in each of the several figures, Figure 1, Sheet 1, is a top plan of the improved instrument, and Fig. 2 is a bottom plan of the same. Fig. 3, Sheet 2, is a sectional view of the instrument, taken on line X of Fig. 1. Fig. 4 is a longitudinal section taken through line Y of Fig. 3. Fig. 5 is a plan of a certain elastic diaphragm used in connection with an air chest or chamber, *n*, forming part of the device. Fig. 6 is a plan of a certain casting in detail, which is used in connection with or forming a part of a key of the instrument. Fig. 7 is a side view of the same, and Fig. 8 is a sectional view on line Z. Figs. 9 and 10 are perspective views of pieces adapted to be inserted in the air-chamber and one of which serves as a bed for the keys, and Fig. 11 is a plan of a reed.

In said drawings, *a* indicates a case, frame, or bed. *b b* are the keys, arranged therein after the general plan of the keys of a piano or organ, the same being arranged on fulerumal bearings *c*, Figs. 2 and 3, preferably consisting 50 of a longitudinal strip which extends from one end of the case to the other, said keys being held down thereon by a spring, *d*, which

may be a rubber band or ring, as shown in Fig. 3, or, and preferably, a spiral wire spring at the outer end of the keys. The outer movements of the keys when depressed by the fingers are limited by the bearings *c c*, which are also preferably a strip which extends longitudinally through the case, the said bearing being provided with cushions *ff*, by means of 55 which the sound caused by impact is prevented.

At or near the end of the keys *b* are metallic extensions *g*, upon which the reeds *h* have bearings, the said extensions being cast from 60 suitable material—such as metal or other hard material—but preferably of metal. The upper part of the metallic extensions or parts *g* may be recessed, as indicated in Fig. 3, to provide a seat for the reeds. The latter may 65 be removably adjusted therein, being held in place by the screw *i*, although it may be permanently secured in place. Below said reeds within the said extensions *g* is formed a chamber, *j*, which conveys the air from the 70 air-chest of the reed-tongue, which vibrates 75 under the influence of said air to produce musical sounds in the ordinary manner. The said extensions *g* have an outward projection, *k*, Figs. 3, 7, and 8, and through the same extends an air-passage, *l*, which communicates 80 with the chamber *j*. The said outward projection is preferably tubular in shape, as shown, and said projection passes through a rubber or other elastic diaphragm, *m*, and an 85 air chamber or box.

The air-chamber is formed of wood or, and preferably, of sheet metal—such as tin—inclosed or boxed in wood. The said air-chamber extends longitudinally through the case 90 from one end to the other and lies beneath the inner ends of the keys or extensions *g* thereof. The upper side of the box is inclosed from end to end with a rubber or elastic diaphragm, *m*, above referred to, the said rubber or elastic 95 diaphragm being cemented to the sides of said box, so as to prevent the escape of air from the air-chamber *n* within said box. By forming the chamber of tin the same is prevented from corroding or being otherwise damaged by the 100 moisture from the lungs of the player when the same condenses therein.

The diaphragm is provided, preferably at about the center thereof, with a longitudinal se-

ries of perforations, *oo*, Fig. 5, of about the size or smaller than the projection *k* of the keys, so that when said projections are formed through the same the elastic partition thereby closely 5 hugs the said projections and moves therewith as the said projection moves vertically under the influence of the fingers without allowing the escape of air at the joints. Below the diaphragm, extending longitudinally 10 through the air-chamber, is a seat, *p*, upon which the extensions *k* find bearings when drawn down by the spring *d*. The upper side of said seat is cushioned, first by a thickness of felt and then on the top by a thickness of leather, 15 preferably sheep-skin, against which the tubular extension *k* bears. The passage *l* therein is thus closed, so that the air from the chamber is prevented from entering the chamber *j* and causing the tongue of the reed to vibrate.

20 When the keys *b* are depressed by the fingers, the extensions or tubes *k* are raised from engagement with the seat or bed *p*, the passages *l* are open, and the air from the air-chamber *n* is allowed to pass upward through the passage 25 *l* and chamber *j* and to vibrate the tongue of the reed, so that musical sounds are produced.

At the sides of the air-chamber or the metal casing forming the same is formed a passage, *q*, which extends longitudinally along the said 30 casing and is provided with openings *r r* at the opposite ends of the chamber *n*, and at or near the center of said passage *q* the same, as at *s*, communicates with a tube or duct, *t*, which is or a part of which is of rubber or other flexible tubing of sufficient length to allow the same 35 to be raised to the mouth of the player. At the outer extremities of said tubing *t* the same is or may be provided with a mouth-piece, *u*, and as the player blows into the mouth-piece *u* 40 the air passes through the tube *t* into the passage *q*, where it is divided and passes into the opposite ends of the chamber *n*. By forcing air into the opposite ends of the air-chamber, as described, I am enabled to cause both the 45 keys of the high notes and the keys of the low notes to speak or vibrate simultaneously.

The extensions *g* may have and preferably do have integral therewith suitable formations to engage with the fulcrum bearing *c* 50 or with a pivotal wire, *v*, disposed on the top thereof, the said formation being marked *w* in Fig. 7 and being adapted to prevent the keys from moving inward or toward the air-box in said casing. The said fulcrum bearings are 55 also provided with pins 2, which are adapted to engage perforations or recesses 3 in the extension and prevent said keys from moving sidewise on their bearings.

The case *a* is or may be provided with a 60 piece, 4, which may be cushioned, as at 5, the said bearing 5 serving as a stop for the keys and forming with the rear portion, *a'*, of the case *a* a longitudinal chamber, *a''*, which is closed by a hinged door or cover, *a''*. The 65 strip 4 may be removed, it being simply held in receptacles or bearings at the ends of the case *a*, and when removed the keys may be

readily withdrawn or removed by simply disconnecting the springs *d* from their bearings.

The interior of the box forming the chamber *n* may be and preferably is varnished to prevent any injurious effects of moisture, and the parts *p* arranged within the air-chamber may likewise be varnished to prevent the aforesaid effects from moisture.

I may provide a valve or opening, 6, at or near the bottom of the chamber *n* to allow the escape of any condensed moisture should the same accumulate in said chamber.

The construction of the bearing *p* is shown 80 more clearly in Figs. 9 and 10, in which end pieces, *p'*, are suitably mortised to receive the longitudinal bearings *p*, the said end pieces extending across the box and the bearing *p* lying in the middle of the chamber. The said end 85 pieces are provided with cushions 7 on the under side to deaden any sound produced when operating the keys.

Having thus described the invention, what I claim as new is—

1. In a musical instrument, the combination, with a series of keys, *b*, having reeds thereon, of an air-chamber and flexible tube connected therewith and adapted to carry the air from the mouth of the player to said air-chamber, 95 said parts being arranged and adapted to operate substantially as and for the purposes set forth.

2. In a reed instrument, the combination, with a series of keys having reeds thereon and 100 moving therewith, of an air-box having a flexible diaphragm adapted to close around the portion of the reed having the air-passage to allow of the movement of the reed and prevent the escape of air excepting through 105 said air-passage, substantially as and for the purposes set forth.

3. The combination, with a case having a fulcrum bearing, *c*, and stops *e*, of keys *b*, disposed on said fulcrum bearing and provided 110 with an extension, *g*, having reeds *h*, and an air-chamber provided with a perforated and flexible diaphragm, *m*, adapted to receive the said extensions, and a seat, *p*, arranged within the said chamber *n* and adapted to close the 115 air-passage through the extension *g*, substantially as and for the purposes set forth.

4. In combination, a case, *a*, keys *b*, arranged on a fulcrum bearing, *c*, springs *d*, extensions *g*, having air-chambers *j* and reeds *h*, a 120 metallic box having an air-chamber, *n*, therein, a seat, *p*, and a suitable duct for conveying the air to said chamber, all said parts being arranged and combined to operate substantially as and for the purposes set forth.

5. In combination, a case, *a*, keys *b*, having reeds therein and a projection, *k*, the said extensions being provided with suitable air-passages, and a chamber, *n*, covered by a perforated diaphragm, *l*, and having thereon a seat, *p*, providing a bearing for said keys, substantially as and for the purposes set forth.

6. In combination, a case, *a*, keys *b*, having reeds therein, and a projection, *k*, the said

projection being provided with suitable air-passages, and a chamber, *n*, covered by a perforated diaphragm, *k*, and having thereon a seat, *p*, providing bearings for said keys, and a spring, *d*, for holding the said extension down upon said seat, substantially as and for the purposes set forth.

7. The combination, with keys and an air-chamber, *n*, arranged and co-operative therewith, substantially as set forth, of an air-passage, *q*, arranged at the sides of said chamber *n* and provided with openings from said passage to said chamber at the opposite ends of said chamber, and a duct, such as a tube, *t*, leading into said passage *q*, substantially as and for the purposes set forth.

8. In a musical instrument substantially such as described, the combination, with keys *b*, having reeds and passages for air to said reeds, of an air box or chamber having a perforated diaphragm, *m*, and a seat, said seat being provided with suitable cushions and adapted to close the air-passage formed in said keys, substantially as and for the purposes set forth.

25 9. In a musical instrument, a series of keys having thereon reeds *h* and means for conveying air to said reeds for vibrating the tongues therein, substantially as and for the purposes set forth.

30 10. In a musical instrument, a reed and a key, the two being connected, the said reed being opened to allow the passage of air therethrough by the depression of said key, substantially as and for the purposes set forth.

11. In combination with a case, *a*, having 35 a suitable fulcrumal bearing therein, a series of keys disposed upon said bearing, said keys being provided with reeds *h*, an air-passage to said reeds, and an air-chamber connecting with said air-passages in said keys, substantially as 40 and for the purposes set forth.

12. In combination with keys *b* of a musical instrument and extensions *g* thereof, reeds *h*, removable from said extensions, substantially as and for the purposes set forth. 45

13. In a musical instrument, the improved key herein described, having a cast-metal extension, *g*, providing fulcrumal bearings, an air-passage, and a reed arranged thereon, all said parts being arranged and combined substantially as and for the purposes set forth. 50

14. In a musical instrument, the combination, with a series of keys having reeds arranged thereon and having passages therein leading to said reeds, of an air-chamber provided with a rubber diaphragm and a seat for said keys within said chamber, the said keys extending or projecting through said diaphragm to said seat *m*, substantially as and for the purposes set forth. 55

In testimony that I claim the foregoing I have hereto set my hand this 11th day of January, 1888. 60

MAX BRAUN.
